See application file for complete search history.

FIG. 1 is a perspective view of an embodiment of a kiosk showing our new design.

FIG. 2 is a front elevation view of the kiosk of FIG. 1.

FIG. 3 is a back elevation view of the kiosk of FIG. 1.

FIG. 4 is a first side elevation view of the kiosk of FIG. 1.

FIG. 5 is a second side elevation view of the kiosk of FIG. 1.

FIG. 6 is a top plan view of the kiosk of FIG. 1; and,

FIG. 7 is a bottom plan view of the kiosk of FIG. 1.

The portions of the drawings shown in broken lines represent environmental structure and form no part of the claimed design.

1 Claim, 4 Drawing Sheets**Related U.S. Application Data**

11, 2014, now Pat. No. Des. 742,870, which is a continuation of application No. 13/475,625, filed on May 18, 2012, now Pat. No. 9,256,719.
